UNITED STATES PATENT OFFICE.

SAMUEL ENGLISH, OF PITTSBURGH, PENNSYLVANIA.

TRACK-TERMINAL.

1,334,896.

Specification of Letters Patent. Patented Mar. 23, 1920.

Application filed October 27, 1919. Serial No. 333,591.

To all whom it may concern:

Be it known that I, SAMUEL ENGLISH, a citizen of the United States, residing at Pittsburgh, in the county of Allegheny and State of Pennsylvania, have invented new and useful Improvements in Track-Terminals, of which the following is a specification.

This invention relates to track terminals or abutments and has for its primary object the provision of means for stopping the travel of cars without injury to either the cars or the terminal.

Another object of the invention is the provision of a track terminal which is located in the path of a car and frictionally engageable with the track for the purpose of gradually stopping the progress of the car without the usual shock or jar.

Another object is the provision of a track terminal of the above character having a wear plate, which is removable, so that the said plate may be replaced, when desired.

A further object is the provision of a slide- 25 able track terminal having means for turning the same to normal position after being released by the car.

Other objects and advantages of the invention will appear as the following description is read in connection with the accompanying drawings.

In the drawings:

Figure 1 is a plan view of a fragmentary portion of a track, with the invention applied thereto.

Fig. 2 is a side elevation of the same.

Fig. 3 is an enlarged transverse sectional view on the line 3—3 of Fig. 1.

Fig. 4 is a longitudinal section on the line 40 4—4 of Fig. 1.

Fig. 5 is a transverse section through the track showing the opening in the road bed for housing the counter-balance weights.

Fig. 6 is a detail perspective view of the 45 shoe.

Fig. 7 is a similar view of the wear plate.

Referring in detail to the drawings, like characters of reference denote corresponding parts throughout the several views.

In carrying out the invention, it is preferred to bend the ends of the rails slightly upward, so as to provide an inclined road bed, as shown at 10, although this in some cases may not be essential.

Mounted upon each rail of the track, is a shoe 11; the latter comprising a top wall 12

and side walls 13 and 14, the shoe being shaped substantially to conform to the shape of the rail head, as shown in Fig. 3. The receiving end of the top wall is slightly tapered, as is also the extremity of the wall 14, as indicated at 15. The wall 14 is disposed upon the inside of the rail, the taper 15 permitting the flange of the wheel to ride easily along the inner face of the shoe. The opposite end of the shoe 11 is upwardly curved, as indicated at 16, so as to form a seat or abutment for the tread of the car wheel, and when the said wheel engages this abutment, the shoe will slide along the rails under the impetus of the car. By reason of the particular cross sectional shape of the shoe, the latter will be capable of sliding movement, but will be held against unauthorized removal. The said shoe, however, may be removed by sliding the same longitudinally over the end of the rail.

Located within the shoe, is a wear plate 17, the latter comprising a relatively thick metal bar, which is beveled at one end, as indicated at 18, so as to permit the car wheel to readily ride upon the top of the shoe. The opposite end of the bar 18 is provided with a curved extremity 19, which is located within a pocket 20, formed by the upwardly curved end 16 of the shoe. The wear plate is held in position within the shoe through the medium of a removable pin 21, which passes through registering elongated slots formed in both the shoe and wear plate, so that the plate may be easily replaced, the said pin serving to hold the plate against accidental removal, as will be hereinafter apparent. The pin 21 fits loosely within the slots, enabling the plate 17 to remain seated after wear.

In the use of the invention, a car riding upon the shoe will cause the latter to travel up the inclined portion 10 of the track a distance governed by the speed and weight 100 of the car, the rails being provided at their extremities with upturned portions 22 to limit the movement of the shoe.

After the shoes have reached their limit of movement, the car will then descend the incline, the wheels leaving the shoes, and for the purpose of returning the shoes to their normal position, each shoe has connected thereto a chain or cable 23, which passes over a pulley 24, located adjacent the inside of the rails. The opposite ends of the chains or cables 23 have secured thereto

counter-weights 25, which are housed within an opening 26 provided between the tracks. This opening may be formed in any suitable manner, such as of concrete construction and may be provided with a cover 27, having openings 28 therein for the passage of the chains or cables.

For the purpose of conveniently connecting the chains or cables to the shoes, each 10 shoe is provided along its lower edges with a tubular portion 29, formed by rolling the edge of the shoe, as indicated in Figs. 3 and 6, the rope or cable being passed through one of these tubular portions and provided 15 upon its extremity with a suitable stop 30, which is of sufficient size to prevent its passage through the tubular portion 29.

The invention is susceptible of various changes in its form, proportions and minor 20 details of construction and the right is herein reserved to make such changes as properly fall within the scope of the appended claims.

Having described the invention, what is 25 claimed is:

1. The combination with a car rail, of a friction shoe embodying a housing adapted to receive the head of the rail, means where-

by the shoe may be removably and slidably secured to the rail, a wear plate carried by 30 the casing for contact with the rail tread and means for returning the shoe to normal position.

2. The combination with a car rail, of a shoe comprising a casing removably secured 35 to and slidable along the head of the rail, an upwardly extending extremity located at one end of the shoe to provide a pocket, a wear plate located within the shoe for contact with the head of the rail and an offset 40 extremity for said wear plate for insertion in said pocket.

3. The combination with a car rail, of a shoe comprising a casing removably secured to and slidable along the head of the rail, an 45 upwardly extending extremity located at one end of the shoe to provide a pocket, a wear plate located within the shoe for contact with the head of the rail, an offset extremity for said wear plate for insertion 50 in said pocket and a removable pin extending through openings in the wall of the pocket and the offset extremity of the wear plate.

In testimony whereof I affix my signature. 55
SAMUEL ENGLISH.
